UNITED STATES PATENT OFFICE.

ALBERT D. HEYL, OF NEW YORK, N. Y., ASSIGNOR TO QUIGLEY FURNACE AND FOUNDRY COMPANY, A CORPORATION OF MASSACHUSETTS.

ANTICLOGGING DEVICE FOR PULVERIZED-FUEL CONTROLLERS.

1,193,016.

Specification of Letters Patent. Patented Aug. 1, 1916.

Application filed January 23, 1915. Serial No. 4,032.

To all whom it may concern:

Be it known that I, ALBERT D. HEYL, a citizen of the United States of America, residing at New York city, county and State of New York, have invented certain new and useful Improvements in Anticlogging Devices for Pulverized-Fuel Controllers, of which the following is a specification.

My invention relates to mechanism for feeding finely divided material, such as pulverized coal, and comprises an attachment designed to be applied to apparatus of a standard type employed for this purpose and which greatly facilitates its operation.

A standard type of mechanism, known as a controller, for feeding pulverized coal to furnaces comprises a magazine or chamber to which the pulverized coal is delivered by a hopper or equivalent device, a feed screw conveyer which rotates continuously and forces a regulated quantity of the coal from the magazine along a conduit to be dropped in front of a transverse air blast which picks up as much of the coal as it can carry to the furnace, while the surplus drops below the air blast, and is returned to the magazine by an upwardly inclined return screw conveyer operating in a second, and lower conduit. The material so returned to the magazine meets the downwardly and outwardly flowing currents of material being produced by the action of the upper feed screw conveyer, and the two currents jam together in struggling, twisting masses, the friction of which, one upon another, absorbs a great deal of power unnecessarily.

I have discovered that if a suitable shield be placed in the magazine over the rear end of the feed screw and the delivery end of the return screw, the currents or material flowing downwardly from the hopper are deflected from the first few turns of the thread on the feed screw, and that portion of the screw is left free to receive the returning material from the return screw conveyer, so that it may readily seize said material and drive it out again across the magazine in unison with the downwardly flowing currents from the hopper. As a result both the new material and the returned material travel out to the feed conduit without the packing and crowding together under the action of conflicting forces, which occurs if my improvement is not employed.

The best form of apparatus at present

known to me embodying my invention is illustrated in the accompanying two sheets of drawings in which—

Figure 1 is a vertical central section of a standard form of controller with my invention applied thereto, the hopper being partly broken away; Fig. 2 is a cross section and front elevation on the line 2—2 of Fig. 1, and Fig. 3 is a detail perspective view of the attachment constituting my invention.

Throughout the drawings like reference characters indicate like parts.

1, is the casing of the controller, and 2, the magazine surmounted by the hopper 3. A feed screw conveyer 4, extends across the magazine and out through a feed conduit 14, at the front of the magazine. From conduit 14, the material drops across a transverse air blast passing out through opening 16, the surplus material not carried off by the air blast being returned by conveyer screw 5, through the lower and upwardly inclined conduit 15, to the magazine. Conduit 15, is parallel to the inclined bottom 17, of the magazine, and extends partway into the magazine, continuing nearly to the rear wall thereof as a U-shaped channel 9. The two conveyer screws are rotated in unison by intergearing 6, and driven by electric motor 8, through gearing 7. The foregoing is a brief description of a standard form of controller in successful use for a number of years, but heretofore subject to the disadvantage that the outgoing and return currents of material jam together around the feed screws in the lower part of the hopper and clog the action of the same so that a large percentage of the power is always consumed in overcoming internal friction, especially when the air blast is reduced in force and the volume or surplus material returned to the magazine is correspondingly large.

According to my invention, 10, is a shield, preferably of an inverted U-shape as shown, placed over the rear end of the feed conveyer 4, and over the delivery end of the return conveyer 5, and over the U-shaped channel 9, in which it lies. This shield extends back to and in contact with the rear wall of the magazine. Preferably it has its upper surface inclined upwardly and backwardly to meet said rear wall at an angle as shown, and has laterally extending wings 11, 11, inclined to fit the inclined bottom 17, of the

magazine. These wings may have bolt holes 12, 12, through which bolts 13, 13, may pass to hold the shield in place, or other attaching means may be used.

5 In operation, the first one or two turns of the screw thread on feed conveyer 4, being under shield 10, are not reached by the currents of fresh material flowing down from hopper 3, but are left free to receive 10 the returned material driven up along channel 9, by return screw conveyer 5. This returned material is thus picked up easily by the feed screw and forced out from under the shield without meeting any opposing 15 currents. As it issues from under the shield, the currents of new material sliding down the inclined outer surface of the shield mingle readily with it and the whole mass is driven across to conduit 14, without jamming or packing together unnecessarily. 20 The use of this simple attachment in some cases reduces the consumption of current needed to drive the controller to one third or less of the amount required to operate 25 it before my invention was applied.

Having described my invention, I claim:

1. In an apparatus for feeding finely divided material the combination with a magazine having a forwardly and downwardly inclined bottom, a conduit extending horizontally from its front end, a feed screw conveyer extending across the magazine and out through said conduit, a second conduit 30 extending from the front end of said magazine parallel to said bottom, terminating in a channel of U-shaped cross section in said bottom at the rear of the magazine, and a return screw conveyer in said inclined conduit and channel, of an inverted U-shaped shield adapted to be bolted to the inclined bottom of the magazine in contact with the rear wall thereof over the U-shaped channel and the ends of both conveyer screws.

2. In an apparatus for feeding finely divided material the combination with a magazine having a forwardly and downwardly inclined bottom, a conduit extending horizontally from its front end, a feed screw conveyer extending across the magazine and out through said conduit, a second conduit 40 extending from the front end of said magazine parallel to said bottom, terminating in a channel of U-shaped cross section in said bottom at the rear of the magazine, and a return screw conveyer in said inclined conduit and channel, of an inverted U-shaped shield adapted to be bolted to the inclined bottom of the magazine in contact with the rear wall thereof over the U-shaped channel and the ends of both conveyer screws.

2. In an apparatus for feeding finely divided material the combination with a magazine having a forwardly and downwardly inclined bottom, a conduit extending horizontally from its front end, a feed screw conveyer extending across the magazine and out through said conduit, a second conduit 45 extending from the front end of said magazine parallel to said bottom, terminating in a channel of U-shaped cross section in said bottom at the rear of the magazine, and a return screw conveyer in said second conduit and U-shaped channel, of an inverted U-shaped shield adapted to be bolted to the inclined bottom of the magazine in contact with the rear wall thereof over the U-shaped channel and the ends of both conveyer screws, said shield having its upper surface inclined in the same direction as the bottom of the magazine.

ALBERT D. HEYL.
